DISPLAY DEVICE

Marselius T. Ashe, Garden City, N. Y., assignor
to Barron Collier, New York, N. Y.

Application June 9, 1936, Serial No. 84,260

3 Claims. (Cl. 40—154)

The invention relates to display devices and more particularly to frames for holding advertising cards. It has for its main object to provide a frame of circular shape in which one or more card board discs, or other objects, may be inserted without having to remove any parts of the frame. Another object is to provide a frame in which cards may be displayed from both the front and rear. A further object is to provide a frame of attractive appearance; which may either be suspended by chains, cords or similar means, or be provided with means so that it may be placed on a support; and which can be manufactured at low cost.

These and various other objects and advantages will be readily understood from the following description and from the accompanying drawing of preferred embodiments of the invention, in which, however, modifications may be made without departing from the scope of the appended claims. In the drawing

Fig. 1 is an elevation of the device showing the cards in place in the frame;

Fig. 2 is a cross-sectional side view;

Fig. 3 is another view similar to Fig. 1, but showing the cards in the act of being inserted or removed;

Fig. 4 is a fragmental, cross-sectional view of a frame of slightly modified shape;

Fig. 5 is a front view of a modification of the frame;

Fig. 6 is a side view of Fig. 5;

Fig. 7 is an enlarged fragmental view of the frame illustrated in Figs. 5 and 6, shown with the cards in place; and

Fig. 8 is a similar view, showing a card being inserted.

Referring first to Figs. 1 to 3, the device consists of a circular frame 10 and, in this instant, 40 of two circular advertising cards 11 and 12. An angularly disposed slit 13 is milled, or otherwise formed, in the frame while a notch 14 is cut in the edge of each of the cards. The point 15, which is formed by milling the slit, is preferably 45 pressed slightly inwardly towards the center of the frame, and the frame, which in this instant is shown as circular in cross-section, is provided with a slot 16 in which the cards are held. The frame is suspended by chains or cords 17 which 50 are fastened in eyelets 18 secured on the frame.

The cards are removed from the frame by rotating them in the frame, one at a time, until the straight edge of the notch 14 is engaged by the point 15. This causes the edge to work up 55 through the slit 13 and consequently on the out-

side of the frame, as shown at 19 in Fig. 3. The continuous turning of the cards will "unscrew" them from the frame. The cards are inserted in a similar manner. While I prefer to form a single slit in one side of the frame only, it is evident that one, or more than one, slit might be formed in both sides of the frame.

In Fig. 4 the frame 20 is shown rectangular in cross-section; it, as well as the cards, is otherwise constructed similarly to the frame just described.

Figs. 5 to 8 show a frame somewhat differently constructed. In this case, the frame 21 is split at 22 while the cards 23 and 24 are provided with notches 25 as in the other cards. To insert the cards in this frame, the open ends 26 and 27 of the frame are sprung sideways, as plainly shown in Fig. 8, and the card, starting from the notch, is "screwed" in as in the former case. To hold the frame in the sidewardly-sprung position, a plurality of points 28 and depressions 29 20 are formed on each of the ends of the frame.

The frame is so made that when in the closed position, shown in Fig. 7, it has sufficient tension to hold the ends tightly together. A frame 25 of this construction is preferably suspended by a single cord or chain 30 fastened in eyelets 31 secured on the frame. Either of the frames may be provided with means for standing them on a support, instead of suspending them. In such 30 cases any suitable support may be used, as for example the bracket 32, shown in Figs. 5 and 6.

While I have shown and described two cards used in the frame, it is evident that a single card, imprinted on one or both sides, may be substituted. In like manner, while I have mentioned that the device is particularly well suited for displaying advertising cards, it may, of course, find many other uses.

Having described the invention and its objects, what I claim as new and wish to protect by Letters Patent is:—

1. A display device of the class described comprising a circular frame having an inner circumferential groove, discs adapted to be held in said groove, a slit cut in the frame, a notch cut in the edge of each of the discs, said notches in combination with said slit providing the means whereby the discs may be inserted in and removed from the frame by turning them in relation thereto.

2. A display device of the class described comprising a circular frame having an inner circumferential groove, a disc adapted to be held in said groove, an angularly-disposed slit cut in one side 55

of the frame so as to leave a point extending inwardly to the groove, a notch cut in the edge of the disc, said notch in combination with said point providing the means whereby the disc may be inserted in and removed from the frame by turning it in relation thereto.

3. A display device of the class described comprising a circular frame having an inner circumferential groove, a plurality of discs adapted to 10 be held in said groove, an angularly-disposed slit

cut in one side of the frame so as to leave a point extending inwardly to the groove, a notch cut in the edge of each of the discs, said discs in combination with said point providing means whereby the discs may be inserted and removed from said frame by turning them in relation thereto, and means for suspending the device from a support.
